UNITED STATES PATENT OFFICE.

KERSTIN ÖSTRÖM, OF SILJANSNÄS, SWEDEN.

DISH-WASHER.

954,879.

Specification of Letters Patent. Patented Apr. 12, 1910.

Application filed November 23, 1908. Serial No. 464,011.

To all whom it may concern:

Be it known that I, KERSTIN ÖSTRÖM, a subject of the King of Sweden, and a resident of Siljansnäs, in the Kingdom of Sweden, have invented new and useful Improvements in Dish-Washers, of which the following is a specification, reference being had to the drawings accompanying and forming a part hereof.

10 This invention relates to dish-washers and drainers of the kind in which the dishes are exposed to the cleaning action of water actuated by centrifugal force.

15 The object of the invention is to provide a dish-washer of the said kind in which the water impinging the dishes is strained and caused to circulate so as to effect an efficient washing of the dishes.

20 Further objects of the invention will hereinafter appear.

In the drawings, I have shown, by way of example, two different forms of a dish-washer embodying the invention.

25 Figure 1 is a side elevation of the one embodiment. Fig. 2 is a horizontal section of the same on line A—B of Fig. 1. Fig. 3 is a horizontal section of the same apparatus on line C—D of Fig. 1. Fig. 4 is a plan view of the netting for retaining the dishes in 30 position during washing. Fig. 5 is a central vertical section of the second embodiment. Fig. 6 is a horizontal section of the said latter embodiment.

35 Referring to Figs. 1—4 of the drawings, the apparatus has an outer wall 1 suitably cylindrical in shape and provided, at its top, with a cover 2. The inner wall of the apparatus is similar in shape to the outer one and suitably consists of a cylindrical part 3 having, at its top, a cover 4. The cylindrical wall 3 and the cover 4 are both perforated. The inner wall and the outer one are fitted to a common bottom 5. Situated in the cylindrical part of the apparatus is a door 6 having double walls corresponding to the walls 1 and 3, respectively, so that a water chamber is formed in the door. The dish-washer enters into this chamber through openings in the side-walls 7, 8 and 9, 10, respectively (Fig. 2), and through similar openings in the upper wall 11 of the door and the wall 12 of the door frame adjacent thereto (Fig. 1). Similarly to the wall 3, the inner part of the door is perforated preferably over its whole surface. The door or the

door frame (or both) is provided round about with a suitable packing.

Extending through the bottom 5 of the chamber hereinbefore described is a rotatable shaft 13 journaled in the bottom 5 and 60 in the cover 4 of the inner wall. Attached to the shaft 13 are trays or crates 14 extending round about the shaft and provided with upwardly directed edges, as shown in the drawing. The crates 14 are, suitably, 65 adjustable along the shaft and adapted to be clamped in position by suitable clamping devices (not shown). The crates are perforated, similarly to the inner wall of the wash-chamber, on their whole surfaces and 70 provided, at their upper sides, with suitable devices for retaining the dishes placed on the crates. Obviously, the said devices are to be suited to the kind of dishes to be washed. The dish-holding crates may be 75 formed of wire netting or the like and they may be of the form and size most suitable for holding and retaining the dishes.

Placed above the outer vessel is a tank or receptacle for dish-water, said receptacle 80 suitably consisting of an upper bowl 15 communicating with a chamber situated between the cover 2 and an upper cover 18. Extending through the bowl and through the said chamber is a valve spindle 16 carrying, at its lower end, a valve 17 adapted to close a central opening in the cover 2. Water filled in the bowl 15 thus runs into the chamber between the covers 2 and 18 and fills the said chamber and the bowl. 90 By raising the valve 17 the water is caused to run down into the washing vessel. The vessel is carried by feet 19 so that there is a free space beneath the bottom 5. Placed in the said space is the gearing connected to 95 the shaft 13, said gearing consisting, in the embodiment illustrated, of a bevel gear 20 connected to a pulley 21 driven by a belt and a crank wheel 22 placed at the outer side of the vessel. Placed beneath the bottom 5 is a funnel 23, or the like, said funnel closing against an outlet opening in the said bottom, said opening being regulable by means of a slide 24. The opening and funnel serve as an outlet for the slops, which 105 are thus received by the funnel 23 and led into a collecting vessel or drain.

The netting 25 shown in Fig. 4 may be expanded, in the manner shown in the drawing, in the shape of a circle and is employed 110

to be stretched above and attached to the edges of the crates 14 so as to retain their contents in position. Obviously, such a netting need only be placed above the upper-
5 most crate, inasmuch as the dishes on the other crates may be retained by the upper crate adjacent thereto, which may be lowered into close contact with the contents of the crate under it, each of the upper crates
10 thus forming a cover for the lower crate adjacent thereto.

The apparatus described works in the following manner. The dishes are introduced through the opened door, placed on the
15 crates and fastened in such a manner that they cannot be thrown outwardly when the crates are rotated. The door is thereupon well closed and the bowl 15 and chamber below it are filled with hot water. The
20 crates with the dishes are caused to rotate and the valve 17 is opened. The dish-water now runs through the cover 4 into the vessel which is filled with water to a greater or smaller height. During the rotation of the
25 crates the dishes are washed by the water which, on account of the rotation, is at the same time thrown out into the space between the walls 1 and 3. The remains of food are separated at the inner side of the perforated
30 wall 3 and the water rises along the inner side of the wall 1 and returns through the cover 4 into the perforated washing vessel in order to again circulate as described. When the crates have rotated a few minutes,
35 the slops are drawn off through the opening in the bottom of the vessel and the funnel 23. Thereupon the opening is again closed and hot water, preferably with carbonate of
soda or the like dissolved therein, is admitted, whereupon the rotating and drawing off of the slops is repeated. When a further
40 quantity of water has been admitted and drawn off, the speed of rotation is increased for draining the dishes.

45 Referring now to Figs. 5 and 6, the apparatus comprises a frame 26 carrying a vessel 27 the bottom of which is provided with an outlet of a comparatively large cross-sectional area regulable by means of a
50 tap or cock 28. Placed within the vessel 27, at a suitable distance from the wall, is a cylinder 29 of perforated sheet-metal, said cylinder being attached to and carried by the bottom of the vessel 27. The cylinder
55 29 is provided with a cover 30 which suitably slopes toward the center where the cover has a large opening 31. Provided at the sides of the said opening are other openings 32. Placed within the stationary cylinder 29 is a rotary basket 33 made of perforated sheet-metal, netting, or the like, said basket being placed at a distance from the stationary cylinder 29 so as to leave a space 34 between the said cylinder and the basket. The basket is carried by

a vertical spindle 35 adapted to be rotated by a crank 36 connected by suitable gearing to the said shaft, as shown in Fig. 5. The vertical wall of the basket 33 is provided with obliquely set slits 37 cut in the wall from the upper edge down to the bottom and the edges of said slits are bent inwardly so as to form inwardly directed, obliquely extending wings. When the basket rotates in the direction indicated by the arrow in Fig. 6, the wings will catch the liquid within the basket and the remains of food removed from the dishes and carry same into the space 34. The water continues through the wall of the cylinder 29 which works as a strainer so as to retain the remains of food in the space 34. The water which has entered into the space 38 between the cylinder 29 and the outer vessel 27 rises along the wall of the latter and arrives at the cover 30 upon which it runs toward the center and through the openings 31 and 32 therein down upon the dishes in order to again impinge the latter and stream outwardly in the same manner as before as long as the crank is rotated.

The dishes inclosed within the basket 33 are suitably placed in holders of any convenient shape and construction, said holders being, preferably, suited to the dishes to be washed. In the drawing (Figs. 5 and 6) I have shown a holder 39 for common plates, said holder consisting of two lower bars and one upper bar connected together at their ends by suitable end-pieces, and having a number of corresponding recesses for the plates which are placed on edge in the said holder, one behind the other, in such a position that the water impinges and streams past the same. Dishes of other form, such as cups, glasses, and the like, are placed in other holders and in the position in which they are most easily accessible to the impinging and whirling water.

The apparatus last described may be used in the following way: Hot water is poured on the greasy plates and the like, the cock 28 being kept open. The cock is thereupon shut off and the apparatus is filled to about $\frac{1}{3}$ of the depth of the basket 33 with hot water which has been made soapy or in condition to dissolve grease from the dishes. The cock 28 is thereupon opened for a while, in order to drain off remains of food sunk to the bottom of the apparatus, whereupon it is again closed. The crank 36 is then slowly turned for a minute, whereupon the speed is increased. This increase in speed causes the water to rise in the outer space 38 and to stream back toward the center. When the apparatus has thus been running about 3 minutes, the washing is almost completed, and while the crank is still rotated all the water is rapidly drawn off. The cover 30 is thereupon removed, without the

apparatus being stopped, and a few scoops of hot water are poured on the dishes, while the cock is kept open, so that the water rapidly runs off. The speed of rotation is now increased and continued for a minute so as to dry the dishes. The apparatus is thereupon stopped and the dishes are left for a while for allowing the water to evaporate. When the dishes are then removed, 10 they are dry and clean, at least as far as porcelain vessels are concerned, whereas glasses and the like may sometimes require a short subsequent drying.

In conclusion I wish to point out that I 15 do not restrict myself to the precise details of construction and arrangement hereinbefore described and illustrated, since it is obvious that the apparatus may be varied considerably and in many particulars without departure from the principle of my invention.

I claim:

1. In a dish-washer, the combination of a vessel, a perforated casing inside the said vessel, at a distance from the wall thereof, 25 a cover at the top of the said casing, said cover having openings allowing water to run down therethrough, a rotary basket situated inside the said casing, and means 30 for rotating the said basket, substantially as and for the purpose set forth.

2. In a dish-washer, the combination of a vessel, a perforated casing inside the said vessel, at a distance from the wall thereof, 35 a cover at the top of the said casing, said cover having openings allowing water to run down therethrough, a rotary receptacle situated inside the said casing, said receptacle having slits in the wall thereof, inwardly extending flanges on one edge of the said 40 slits, and means for rotating the said receptacle, substantially as and for the purpose set forth.

3. In a dish-washer, the combination of a vessel, a perforated casing inside the said vessel, at a distance from the wall thereof, 45 a cover at the top of the said casing, said cover having openings allowing water to run down therethrough, a rotary receptacle situated inside the said casing, said receptacle having slits extending obliquely from the top of the receptacle to the bottom thereof, flanges extending inwardly and forwardly from the rear edges of the said 50 slits, and means for rotating the said receptacle, substantially as and for the purpose set forth.

KERSTIN ÖSTRÖM.
